Att'y.

UNITED STATES PATENT OFFICE.

WARREN DRAPER, OF BLASDELL, NEW YORK, ASSIGNEE TO GENERAL ELECTRIC COMPANY, A CORPORATION OF NEW YORK.

HEADLIGHT-DIMMER.

1,281,916.

Specification of Letters Patent. Patented Oct. 15, 1918.

Application filed August 15, 1916. Serial No. 114,897.

To all whom it may concern:

Be it known that I, WARREN DRAPER, a citizen of the United States, residing at Blasdell, in the county of Erie, State of New York, have invented certain new and useful Improvements in Headlight-Dimmers, of which the following is a specification.

My invention relates to a dimmer or screen for a headlight, and has for its object the improvement in a device of this character.

For certain classes of service, and particularly for interurban trolley cars, headlights are required which project a powerful beam of light, in order that objects may be detected well in advance of the car. Within city limits, however, the use of an intense light of this character is objectionable inasmuch as it exerts a blinding effect on pedestrians and on the operators of other vehicles, and laws have been passed in a great many municipalities forbidding the use within the city limits of headlights having dazzling lights. In accordance with my invention, a screen is provided between the light source and the window of the headlight, which is operable from without the headlight, and which is related to the coöperating parts in such a way as to form a simple and compact arrangement, and one in which the screen is readily moved either to a position to intercept the direct rays from the light source, or to a position where the rays are permitted to pass freely through the window or lens of the headlight. My invention also provides a device of this character which is positively held by gravity in each of these positions.

In the accompanying drawings in which I have shown one embodiment of my invention and in which like reference characters are applied to like parts, Figure 1 is a longitudinal section through a headlight embodying my invention; Fig. 2 is an elevation on the line 2-2 of Fig. 1; and Fig. 3 is a plan view of certain details.

Referring now to the drawings, 10 is the casing of a headlight which may be of the usual form, and which may be attached to the front 11 of a car by means of the usual straps 12. The headlight is provided with a window or lens 13 which may be of any desired construction.

I have illustrated my invention in connection with a luminous arc headlight; that is to say, a headlight in which the source of

light is an arc formed between a non-consuming electrode and a consuming electrode emitting vapors which, when introduced into the arc, lend luminosity to the same. It will be understood, however, that my invention is equally applicable to headlights in which a different character of arc is produced, and in fact to headlights in which other light sources are employed. The upper non-consuming anode is represented by the reference character 14, and the lower consuming cathode by the reference numeral 15. The upper electrode is preferably provided with radiating wings 16 which engage slots in a chimney 17, which carries away the vapors produced by the arc, all as is well understood in the art. The lower electrode is supported on an arm 18 which is pivoted to a stationary bracket at 18^a, and is connected by a link 19 to one end of a lever 20 pivoted at 20^a. The opposite end of this lever is connected by a bar 21 and clutch 22 to the armature 23 of an electromagnet 24. The construction and operation of these parts are well understood in the art, and as my present invention is not concerned with the particular mechanism by which the electrode is operated, this mechanism will not be further described.

A disk shaped dimmer or screen 25 which is preferably bent over at its upper part, as at 26, is secured to an arm 27. This arm extends along the diameter of the dimmer beyond the center thereof, and is formed at its lower end with a heavy boss 27^a. The arm has at its upper end ears 28 and 29, the former of which projects at right angles to the plane of the screen while the latter is bent over into a plane parallel with said screen. A shaft or bar 30, the outer end of which is journaled in a boss 30^a, secured to the casing, passes through the ear 28 and through the sides of a U-shaped bracket 31 and is secured to the ear 29 as by a screw 30^b. In this manner the dimmer 25 which is secured to the bar 27, hangs normally down in a pendulous manner, and by reason of the weighty boss 27^a, the center of gravity of this pendulum is far below its pivotal support. The bracket 31 is preferably somewhat inclined as shown in Fig. 1, and is secured to one of the radiating wings 16 in any convenient manner, as by means of clamping plates 32. The bar 30 is provided with an insulating section as shown at 33. 110

This is inserted to prevent short circuit between the electrodes since one end of this bar and the parts associated therewith are mounted directly on the radiating wing of the upper electrode. A pinion 34 is mounted on the outer end of the bar or shaft 30, and engages a rack 35 formed on the end of a bar 36. This bar passes through guide members 36^a, as indicated in Fig. 3, and extends outside of the casing of the headlight. This bar is operated by a second bar 37 which is here shown as extending through the dashboard 38 of a car, and is provided at this outer end with a handle 39, which is readily accessible to the motorman. The bar 37 is preferably connected to the bar 36 by a hook 40, engaging a corresponding opening 41 in the end of the bar 36, as shown in Fig. 1, in order that the two parts may readily be disconnected when it is desired to remove the headlight from the car. The bar 37 is also preferably provided with a joint as at 42, so that when the bar 37 is disconnected from the bar 36, and is moved to its innermost position, the handle is allowed to drop out of the way beside the dash.

The headlight is preferably provided with a reflector 43 supported by a bracket 44 which is attached to the casing by a screw 45. This same bracket may, as shown, support the chimney and the parts associated therewith.

Assuming that the screen 25 is in the position shown in Fig. 1 by solid lines, it will be observed that it is of a form to intercept all of the direct rays of light from the source, and the only light passing through the lens or window 13 will be that which is redirected from the reflector 43. Now, if it is desired to project a powerful beam from the headlight, it is only necessary for the motorman to pull the handle 39 to the position indicated by dotted lines in Fig. 1, when the rack 35 will rotate in the pinion 34 and cause the screen to be swung upwardly and occupy the position indicated by dotted lines. Since the center of gravity of the screen is below the axis of rotation of the same, when the screen is in the position indicated by full lines in Fig. 1, it will be apparent that the center of gravity will occupy the highest point when the screen has been revolved through 180 degrees, and that when the screen is revolved through something more than this angle to the position indicated by dotted lines in Fig. 1 where it

rests against the bracket 31 which acts as a stop, it will occupy a position of stability where it will be positively held even when subjected to the vibrations and jars incident to the movement of the vehicle on which it is carried.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:

1. In a headlight comprising a casing, a front lens or window, and a source of light, a horizontally pivoted pendulous screen having its center of gravity remote from the pivot and movable from a substantially vertical position in stable equilibrium between the source of light and said window upward through something more than one hundred eighty degrees to another position of stable equilibrium, a stop for said screen in its upward position, and means for thus moving said screen.

2. In a headlight comprising a casing, a front lens or window, and a source of light, a horizontally pivoted pendulous screen having its center of gravity remote from the pivot and movable from its free pendulous vertical position between the source of light and said window upwardly through something more than one hundred eighty degrees to a position of stable equilibrium, a stop for said screen in its upward position, and means comprising connections extending without the casing of said headlight for moving said screen to its respective positions.

3. A headlight comprising a casing provided with a window and a source of light within the casing, a pendulous screen movable from its free position of stable equilibrium between the source of light and the window to another position of stable equilibrium out of the path of light through the window, means for thus moving the screen, and a stop for the screen in its second position.

In witness whereof I have hereunto set my hand this 12th day of August, 1916.

WARREN DRAPER.
